UNITED STATES PATENT OFFICE.

FREDERICK C. HERSEE, OF ROSLINDALE, MASSACHUSETTS.

TIMER.

1,128,978.

Specification of Letters Patent. Patented Feb. 16, 1915.

Application filed July 13, 1914. Serial No. 850,809.

To all whom it may concern:

Be it known that I, FREDERICK C. HERSEE, a citizen of the United States, and resident of Roslindale, county of Suffolk, Commonwealth of Massachusetts, have invented an Improvement in Timers, of which the following description, in connection with the accompanying drawings, is a specification, like characters on the drawings representing like parts in each of the several views.

The present invention relates to timers for internal combustion engines of the type wherein a rotating contact comes into wiping engagement with a series of relatively fixed contacts spaced apart around the orbit of its path of movement.

A prime object of the invention is to provide a timer of this character that is simple and cheap to construct and equipped with an effective wiping contact adapted to present a fresh contacting surface at each engagement along with sufficient friction action against the coöperating contact to make the electrical connection reliable.

A further object is to provide a construction of timer casing, bearing the stationary insulating contacts that may be very cheaply and easily produced preferably by pressing the same to the required contour from sheet or plate material.

The above and other objects and features of the invention will be better understood from the following detailed description taken in connection with the accompanying drawings and will be thereafter pointed out in the appended claims.

Referring to the drawings—Figure 1 shows an end view with parts broken away in section of my invention in one embodiment thereof; Fig. 2 is a central lengthwise section through the form shown in Fig. 1; Fig. 3 is an end view with a part sectioned away showing a slightly modified form of housing holding the stationary contacts; Fig. 4 is a similar view showing another modified form; and Fig. 5 is a lengthwise vertical section through the form of the invention shown in Fig. 4.

Referring to Figs. 1 and 2, the timer housing 10 is shown as of a usual part-cylindrical, part-conical formation with the timer shaft 11 mounted concentrically therein. In this housing are mounted a series, shown as four of equally spaced apart radial contacts. Each of these contacts as shown consists in a metallic ball 12 slidably fitted in

a barrel 13, the inner end of which is turned as seen at 14 to hold the ball while permitting it to project somewhat therefrom. The exterior of this barrel is threaded and fitted within an insulating bushing 15 which may be of hard fiber or other suitable material, this bushing being in turn threaded into a hole in the housing. The outer end of housing 13 is closed by a threaded cap 16 which serves as a backing for a spring 17 contained in the housing and acting on the ball 12 to keep it normally pressed outward.

In accordance with my invention I form the movable rotating contact for coöperation with the balls 12 as a mushroom, or button 18 having a convex head and a stem 19 fitted in a collar socket 20 extending radially from a sleeve 21 fixed to the shaft 11. As best shown in Fig. 2 the mushroom contact 18 is so mounted relatively to the balls 12 that it engages the same, in somewhat eccentric relation wherefrom it results that as the convex surfaces of the ball and of the mushroom head engage each other, the mushroom head being free to turn is moved around somewhat at each contact presenting a fresh surface at each successive engagement, and the ball is also turned oppositely to the mushroom, to some little extent so that a different portion thereof is presented at each contact with the mushroom. By reason of the peculiar partly sidewise engagement of the ball with the mushroom head the balls are so turned that all the different parts thereof are successively presented in operative position so that the wear is substantially even all around the same. It will be further understood that from the nature of this interengagement between the mushroom head and the balls 12, while the head 18 and the ball pressed thereagainst, are turned somewhat each time as described, there will be at the same time, an appreciable degree of rubbing engagement between the contact elements whereby the most effective and reliable contact is obtained. In practice it is found desirable that the mushroom head 18 turn somewhat more freely than it would if it had friction bearing directly against the end of the collar 20. I therefore preferably form the inner end of the stem 19 with a small rounded ball end 34 that projects enough so as to hold the mushroom 18 free of the collar 20, this ball end 34 press-

ng and having bearing against the shaft. 1. It is desirable also to facilitate the turning of the balls 12 and for this purpose I preferably provide a follower disk or block 35 interposed between the spring 17 and the ball so that the turning of the ball is not interfered with by the spring but is relatively free, being pressed on only by the face of the disk 35. Since the mushroom head 18 and the contact balls 12 are the only elements that undergo wear and hence require renewal, it is important that these be easily replaceable. To permit such convenient removal and renewal of the mushroom head at 18 I employ as holding means therefor a transverse pin 22, which may be driven into a hole in the socket 20 positioned so that it passes through one side of an annular recess 23 formed in the stem 19. Thus by merely knocking out the holding pin 22, the mushroom head may be removed and replaced very quickly and easily. It will be understood that the balls 12 can also be instantly removed and replaced merely by unscrewing the caps 16.

In Fig. 3 I show a form of the invention wherein the housing 10' is formed so as to be easily and cheaply pressed or molded from sheet or plate stock. In this form of the invention the housing may be thinner than in the form just described, the peripheral rim flange 24 which this form has in common with the just described form, affording the requisite rigidity. In this form of housing I press in collar sockets 25 from the material of the housing around the contact holes so as to make an extended area into which the insulating bushings 15 may be threaded. In this way a thinner and lighter housing is possible without any sacrifice in the way of rigidity or strength. In the form of the invention shown in Figs. 4 and 5, another means for permitting the use of relatively thin stock in the housing is exhibited. In this form, the housing 10" has unthreaded holes 26 for the contact plugs through which nipples 27 from an insulating ring 28 may be molded, this ring being of any suitable material for the purpose which may be the hard fiber product known as "condensite." In this case the nipples 27 and ring 28 have radial bores 29 into which the contact plugs 13 are threaded. Any suitable means may be employed for fixing the sleeve 21 at the end of the timer shaft 11. As shown the threaded end of the timer shaft is slotted, as indicated at 30 to receive a transverse pin 31 which is transversely fixed by a flange collar 32 at the end of the sleeve 21, and a nut 33 threaded on the shaft end is adapted to be set up to hold the parts assembled.

I am aware that the invention can be embodied in other specific forms as to its several details and I therefore desire the pres-

ent showing to be considered as illustrative and not restrictive, referring rather to the appended claims to indicate the scope thereof.

Having described my invention, what I claim as new and desire to secure by Letters Patent is:

1. A timer, comprising relatively fixed contacts, a mounting therefor, and a revoluble contact mounted to engage said stationary contacts, said revoluble contact consisting in a member mounted to turn on an axis radial of its axis of revolution and out of line with said stationary contacts whereby a turning thereof occurs at each contact to present constantly changing fresh contact portions. 75

2. A timer, comprising a plurality of relatively fixed contacts, a housing therefor, and a revoluble contact having a shaft mounting, said revoluble contact consisting in a mushroom member extending radially of said shaft with its axis out of line with the line of contact with said stationary contacts whereby it is turned each time it engages 90 said stationary contacts to present a fresh contacting portion. 85

3. A timer, comprising relatively fixed contacts, a housing therefor, a revoluble contact having a shaft mounting to be revolved into engagement with said stationary contacts, said revoluble contact consisting in a mushroom member extending radially of said shaft with a stem having a detachable holding device for engaging it with said 100 shaft, said mushroom having its axis out of line with the line of contact against the stationary contacts and adapted to engage the stationary contacts with a rubbing action to be turned at each contact for the purpose 105 stated. 95

4. A timer, comprising relatively fixed contacts consisting in spaced apart spring pressed balls, a housing therefor, and a revoluble contact having a shaft mounting, 110 said revoluble contact consisting in a mushroom member extending radially of said shaft with its axis out of line with the line of contact with said balls, whereby it and the ball contacted are turned at each contact to present fresh contacting portions. 115

5. A timer, comprising relatively fixed contacts, each consisting in a ball with a spring back of the same to press it forward to operative position and an interposed 120 block bearing on the ball, a mounting therefor, and a shaft having a revoluble contact carried thereby for engagement with said fixed contacts, said revoluble contact extending radially of the shaft and in position 125 to engage said balls back and laterally of their most projected portions.

6. A timer, comprising a series of relatively fixed contacts, a mounting therefor, and a shaft having a revoluble contact car- 130

- ried thereby for engagement with said fixed contacts, said revoluble contact consisting in a member mounted to rotate on an axis radial of the shaft, and to engage the stationary contacts at a distance from its axis of rotation, said revoluble contact having at its inner end a reduced rounded head adapted to receive the thrust of contact making and to serve as a bearing therefor.
7. A timer, comprising a series of relatively fixed contacts, each consisting in a ball with a spring back of the same to press it forward to operative position and an interposed block bearing on the ball, a mounting therefor, and a shaft having a revoluble contact carried thereby for engagement with said fixed contacts, said revoluble contact consisting in a mushroom member extending radially of said shaft with a reduced rounded end having bearing against
- the shaft, the axis of said mushroom member being out of line with the line of contact with said stationary contacts whereby it and the balls constituting said stationary contacts are turned at each engagement to present fresh contacting portions.
8. A timer, comprising a series of fixed contacts, a housing therefor formed of plate material with spaced apart holes for the contact plugs having inturned sleeves constituting extended socket areas for said plugs, and a revoluble contact mounted to engage said stationary contacts.
- In testimony whereof, I have signed my name to this specification, in the presence of two subscribing witnesses.
- FREDERICK C. HERSEE.
